UNITED STATES PATENT OFFICE.

JOSEPH MIDDLEBY, OF BOSTON, MASSACHUSETTS.

PORTABLE OVEN.

SPECIFICATION forming part of Letters Patent No. 434,023, dated August 12, 1890.

Application filed September 3, 1889. Serial No. 322,847. (No model.)

To all whom it may concern:

Be it known that I, JOSEPH MIDDLEBY, of Boston, in the county of Suffolk and State of Massachusetts, have invented certain new and useful Improvements in Portable Ovens, of which the following is a specification.

My invention relates to bakers' ovens generally and particularly to "portable ovens," so called.

10 It is the object of my invention to provide means whereby gas escaping from the mouth of the oven when the door of the same is opened may be carried into and conducted through a pipe or flue to the exterior of the building in which the oven is placed, and also to provide new and improved means for supporting the inner bricks or tiles and connecting the same to the outer metallic casing.

20 My improved oven comprises a gas-damper arranged over the mouth of the oven and beneath a flue or pipe which may communicate with the chimney in such manner as that when the oven-door is closed the damper will be automatically operated to close the flue and 25 when the oven-door is opened the damper will of its own gravity swing down, so as to open the said flue and be in position to deflect or conduct the escaping gas into the flue or pipe, and it also comprises the improved detail construction, combination, and arrangement of 30 parts, substantially as hereinafter fully set forth, and particularly pointed out in the claims.

Reference is to be had to the accompanying 35 drawings, and to the letters marked thereon, forming a part of this specification, the same letters designating the same parts in all of the views.

In the drawings, Figure 1 is a front elevation of my improved oven. Fig. 2 is a cross-sectional view of the same. Fig. 3 is a sectional detail showing the construction of the mouth and the arrangement and operation of the gas-damper. Fig. 4 is an end view of 45 a brick or tile used in the construction of the roof or ceiling of the oven.

In the drawings, *a* designates a metallic casing, of suitable form and strength, which may be supported upon legs or standards *b*, arranged at necessary intervals.

c designates metallic I-beams, or metal beams of other form, adapted to rest upon

and be supported by the frame, which beams in turn support tiles or bricks *d*, forming the bottom or floor of the oven, similar tiles or 55 bricks *e*, arranged on edge around the bottom or floor, constituting the side walls.

f are metallic girders or I-beams extending across the frame in the upper part thereof, which girders support the tiles or bricks *g*, 60 which constitute the roof or ceiling of the oven. The edges of the tiles *g* adjacent to the girders *f* are provided with grooves *h*, forming flanges *i, j*, the upper flange *i* being narrower than the lower flange *j*, so that when 65 said grooved edges are brought into position against the said girders the portion *k* of the base of the girder will extend into the groove *h* of the tiles *g*, the edge of the narrow flange *i* resting against the web of the girder and 70 the wider flange *j* extending beneath the said girder and abutting against the like flange of the tile *g* on the other side, and in this way completely covering the girder and protecting it against the direct action of the fire in 75 the oven, and consequently against unequal expansion. With the construction described a space will be left between the lining of the oven and the outer casing, which space may be filled with sand, earth, or other substance 80 that may be readily and cheaply procured and that will serve to retain the heat in the oven.

k' designates the mouth of the oven, to a suitable casing of which is hinged a door *l*. 85 Over the oven-mouth is a pipe or flue *m*, which by means of a pipe may communicate with the chimney or exterior of the room in which the oven is placed.

n is a door hinged below the pipe or flue *m* 90 and constructed and arranged to be engaged by the door *l*, so that when the latter is closed it will engage and move the former, and when the door *l* is opened the door *n* will by its own gravity be opened, swinging from the 95 full to the dotted line position of Fig. 3, opening the pipe or flue *m* and serving as a deflector to deflect and conduct the gas escaping from the mouth of the oven into the said pipe or flue.

o is the ash-box, over which the fire-grate is arranged, said ash-box being provided with doors and means for regulating the draft when a fire is burning in the oven.

p designates links or buckles whereby the portion of the frame supporting the interior walls or lining of the oven is connected with the casing. By these connecting means danger from displacement of parts through expansion and contraction is avoided.

q designates ribs connected with the supporting-frame proper and extending upon the outside of the casing to strengthen the same.

Having thus explained the nature of my invention and described a way of constructing and using the same, I declare that what I claim is—

15 1. A portable oven provided with a mouth and a hinged door to open and close the same, in combination with a gas-flue over the mouth of the oven, and a swinging door to open and close said flue controlled by said oven-mouth door, substantially as set forth.

2. In a portable oven provided with a mouth and door *l*, in combination with a flue *m* above the oven-mouth and a flue-door *n*, pivoted at its upper end and having its lower end arranged to be engaged by the door *l* to be 25 opened and closed thereby, as set forth.

3. In a portable oven, the combination, with the outer metallic casing, of the inner metallic frame, the brick or tiles supported thereby, and the links or buckles *p*, connecting said 30 frame and casing, substantially as set forth.

In testimony whereof I have signed my name to this specification, in the presence of two subscribing witnesses, this 27th day of August, A. D. 1889.

JOSEPH MIDDLEBY.
